UNITED STATES PATENT OFFICE.

ALEXANDER S. SPIEGEL, OF CHICAGO, ILLINOIS.

TILE-IMITATING ROOFING.

1,126,114.

Specification of Letters Patent. Patented Jan. 26, 1915.

Application filed November 2, 1914. Serial No. 869,930.

To all whom it may concern:

Be it known that I, ALEXANDER S. SPIEGEL, citizen of the United States, residing at Chicago, Illinois, have invented certain new and useful Improvements in Tile-Imitating Roofing, of which the following is a specification.

This invention relates to composite roofing and consists in making such roofing in imitation of tile. The imitation tile roofing may be made either in shingle form or in a roll.

The invention consists essentially in placing wooden sticks at intervals between layers of composite roofing to give the ridge effect of tile.

The invention is illustrated in the accompanying drawing, in which—

Figure 1 is a plan view of the improved roofing; Fig. 2 is a longitudinal sectional view, and Fig. 3 is a transverse sectional view; Fig. 4 shows a modification.

In the drawings, the numeral 1 indicates a flat sheet of roofing which comprises the bottom or base of the new roofing.

2 indicates sticks of wooden or other suitable material, such as metal, that is half round with the flat face against the flat sheet 1. These sticks may be varied, however, from half round to suit conditions.

3 indicates a top layer of roofing secured to the bottom 1 and passing over the sticks

2. The two sheets are cemented together and to the sticks by hot compound 4.

The top sheet in passing over the sticks 2 give the resemblance of the ridge of roofing tiles. This roofing is preferably made in strips so that when in place on a roof 40 they will appear as in Fig. 2. As shown in Fig. 3, the bottom sheet 1 is as wide as the sticks 2 are long but the top sheet 3 is slightly wider as at 4, so that when in place this extension 4 will overlap the joint made by the sticks and bottom sheet as at 5. The roofing is held in place on the roof by nails

driven through the sticks under the overlap 4.

If it is desired to have this roofing in shingle form, it would be constructed the same way as the strips except that these would be cut into shingles as seen in Fig. 4. They would be laid with their longitudinal edges overlapping as at 6, as well as with the transverse end overlap 4. Whenever the roofing is laid, all the sticks are in straight rows and their ends contact with each other.

While I have described a plurality of layers or sheets, and this is the preferred form of the roofing, the base sheet or sheets may be omitted without departing from the spirit of my invention, nor do I limit myself to the inserts being of any particular material.

65 I claim:

1. A tile imitating roofing formed of a plurality of layers of roofing and independent insert strips between said layers to form ridges.

70 2. A tile imitating roofing formed of a plurality of layers of roofing and independent strips cemented therebetween to form ridges.

75 3. A tile imitating roofing formed of a plurality of layers of roofing overlapping at their lower edges and independent strips of less length inserted therebetween to form ridges.

80 4. A tile imitating roofing comprising a layer of flexible material with strips secured on the under face of the said layer and suitably secured in place to form ridges in imitation of tile on the outer face of the layer, the said layer being of greater length than the strips, substantially as described.

85 In testimony whereof, I affix my signature in presence of two witnesses.

ALEXANDER S. SPIEGEL.
